Atty's

UNITED STATES PATENT OFFICE.

JOSEPH LESQUENDIEU, OF PARIS, FRANCE, ASSIGNOR TO J. LESQUENDIEU INC., OF NEW YORK, N. Y., A CORPORATION OF NEW YORK.

BOX FOR SALVE OR CREAM.

Application filed January 4, 1927, Serial No. 158,966, and in France June 16, 1926.

The subject of the present invention is a box for salve, cream, rouge, grease-paint and so forth by means of which the salve or the like may be applied without any particular 5 operation and without it being necessary to soil or stain the fingers.

It may be constructed of any suitable material such as metal, wood, ebonite, galalith and so forth.

10 In the accompanying drawing there is illustrated a section and underside plan of one form of construction solely by way of example and to which the invention is not limited as any other suitable shape may be adopted.

15 The box hereinafter described constitutes a clearly defined new industrial product.

The body of the box 1 is provided with a central tubular space 2 ending at its two ends with internally threaded portions 3 20 and 4.

25 With the lower screw threaded portion 3 engages a plug 5 forming a cup 6 which latter is adapted to be advanced in the hollow space 2 by screwing in the plug 5. Into the cup is placed the salve, cream or the like. The screw of the portion 3 is made as easy as possible so that by means of a groove 7 in the outer surface of the plug 5 it is possible to turn this plug by means of the finger-nail and to cause it to rise in the box 1.

30 With the screw threaded portion 4 engages a stopper 8. In addition to forming a closure for the space 2, this stopper is provided on its lower face with a preferably 35 spherical projection 9. The projection and stopper may be of two separate parts or in two parts suitably connected together. The projection 9 is preferably covered with pliant leather so that the surface thereof may 40 be used. It will be readily seen that when the stopper 8 is placed in position on the box, that if the plug 5 is caused to rise in the box the projection 9 will be coated, by reason of the rotation and pressure, with a layer of the cream or the like contained in

the cup. By unscrewing the plug and holding this, this coating may be applied as desired on the lips, cheeks and so forth.

The cream or the like is brought into the required position from time to time by screwing the plug 5 into the box.

No precaution is necessary to prevent the fingers from coming into contact with the cream at any time.

Having thus described my invention, what I claim as new and desire to secure by Letters Patent is:—

1. A box of the character described comprising a tubular member screw threaded at both ends, a plug screwed into one end of said tubular member, a cup adapted to contain salve, cream or the like formed integral with said plug, a stopper adapted to be screwed into the other end of the tubular member, and applicator means on the stopper 65 cooperating with the contents of the cup.

2. A box of the character described comprising a tubular member screw threaded at both ends, a plug screwed into one end of said tubular member, a cup adapted to contain salve, cream or the like formed integral with said plug, and a stopper adapted to be screwed into the other end of the tubular member, and a projection formed on said stopper and adapted normally to be in engagement with the contents of said cup.

3. A box of the character described comprising a tubular member screw threaded at both ends, a plug screwed into one end of said tubular member, a cup adapted to contain salve, cream or the like formed integral with said plug, and a stopper adapted to be screwed into the other end of the tubular member, a spherical projection formed on said stopper, and a layer of pliant leather 85 fitted over said projection, said plug having a diametrical groove for facilitating its turning in the screw thread.

JOSEPH LESQUENDIEU.
